Des. 240,157
Patented June 1, 1976

240,157

LIGHT GUARD

Harry M. Dorn, North Miami, Fla.
(1133 Broadway, New York, N.Y. 10010)

Filed Nov. 13, 1974, Ser. No. 523,399

Term of patent 14 years

Int. Cl. D26—05

U.S. CL. D48—16 B

FIG. 1

FIG. 3

FIG. 2

FIG. 4

FIG. 5

FIG. 1 is a perspective view of a light guard showing my design as viewed from one side having a hinge, the opposite side having a latch;

FIG. 2 is an enlarged rear elevational view of the light guard shown in FIG. 1;

FIG. 3 is a top plan view of the light guard;

FIG. 4 is a side elevational view of the light guard as viewed from the side having a latch; and

FIG. 5 is a bottom plan view of the light guard.

I claim:

The ornamental design for a light guard, substantially as shown and described.
